UNITED STATES PATENT OFFICE.

GARRETT J. BARRY, OF SANDUSKY, OHIO.

MAIL-CRANE AND OPERATING MEANS THEREFOR.

1,360,354.

Specification of Letters Patent. Patented Nov. 30, 1920.

Application filed June 19, 1918. Serial No. 240,728.

To all whom it may concern:

Be it known that I, GARRETT J. BARRY, a citizen of the United States, residing at Sandusky, in the county of Erie and State of Ohio, have invented a certain new and useful Improvement in Mail-Cranes and Operating Means Therefor, of which the following is a full, clear, and exact description, reference being had to the accompanying drawings.

This invention relates to mail cranes, and has for its general object to provide a crane of this character which may be conveniently operated from a moving mail car to automatically bring a mail bag on said crane into operative relation to the catcher with which such cars are ordinarily provided. A further object of the invention is to provide a crane of this character which is generally efficient in operation and which can be conveniently reset after having been operated. Further objects of the invention will be realized in and through the construction and arrangement of the parts illustrated in the drawings forming part hereof, wherein Figure 1 is a perspective view of a portion of a train, showing the manner in which my invention coöperates with the standard mail car equipment; Fig. 2 a sectional elevation 10 of the mail crane and the adjacent track; Fig. 3 a similar elevation of the mail crane, taken at right angles to Fig. 2; Fig. 4 a sectional plan view of the parts shown in Fig. 2; Figs. 5 and 6 sectional elevations, and Fig. 7 a detail in section, of the mechanism for rotating and locking the mail crane shaft; Figs. 8 and 9 details in perspective of the mechanism for rotating the crane shaft; Fig. 10 an elevation of a portion of a mail 20 car showing the manner in which the crane operating mechanism carried thereby is supported and operated, the roller being in elevated position; Fig. 11 a detail of the roller supporting and operating means, showing the roller in its depressed or operating position and Fig. 12 a sectional view corresponding to the line 12—12 of Fig. 10.

The complete mechanism includes a rotary crane shaft having the usual arms for supporting a mail bag, means tending to rotate said shaft to bring a mail bag in operative relation to the catcher on a mail car, a locking device normally preventing the rotation of said shaft, means for disengaging the locking device from operative relation to the crane shaft, and means carried by the car

for automatically operating such disengaging means.

In the drawings forming part hereof, 1 represents one of the rails of a track and 2 a mail coach of a train, said coach having the usual doorway 3 to which there is pivoted the shaft 4 of the mail bag catcher, the catcher arm whereof is indicated at 5 and the operating arm whereof is indicated at 6. 65 Rigid with the shaft 4 is an arm 7 (see Figs. 10 and 11), projecting into the interior of the coach 2 through a slot 8. Connected to the inner end of said arm is a link 9, which is shown as extending downwardly adjacent 70 to the inner wall of the coach and through the floor thereof, with its lower end connected to one of the arms 10 of a lever, the other arm 11 of which is connected to a rod or link 13. The opposite end of the rod or 75 link 13 is connected to one arm 14 of an angle lever, the opposite arm 15 of said lever being connected by a link 16 with a rod 17 carrying a roller 18 at its lower end. The parts 14-17 and the front end of the rod 13 80 are shown as mounted within a housing 19 carried by the floor of the coach, the lever 14, 15 being pivoted to a bracket 20 in said housing and the lower end of the housing being contracted, as shown at 19^a, to provide 85 a vertical guide for the rod 17. The parts are so arranged that, when the catcher is in its inoperative position, the bottom of the roller 18 will be about 5½ inches above the level of the rail 1 and, when the catcher is in 90 the operative position shown in Fig. 1, the bottom of said roller will be substantially at the level of the top of said rail.

21 denotes a vertical housing shown as supported on an extension of one of the 95 cross ties, said housing having a door 22 which may be provided with a lock to permit access to and prevent tampering with the parts therein. The particular cross tie illustrated herein may be a metal channel 100 having its flanges 23 extending downwardly and its web 24 providing a cover for the operating lever therebeneath. A plate 25 is shown as extending transversely of the housing 21 and will be secured to the same 105 in any suitable manner, as by welding, where the housing is of metal. Extending through a central aperture in the plate 25 is the vertical crane shaft 26, said shaft extending through the coverplate 21^a of said 110 housing and being provided with the usual arms 27 and 28 for supporting a mail bag,

indicated at 29 on Fig. 1. The arm 27 is pivoted to a yoke on the top of the crane shaft and is counterbalanced to cause it to assume a vertical position when relieved of 5 the weight of the bag. The arm 28 is pivoted so that it can drop to a vertical position by gravity when the mail bag is disconnected therefrom by the catcher. The construction of the arms 27 and 28 is that 10 ordinarily employed with mail cranes and, in its details, forms no part of my invention.

Suitably secured to the plate 25, as by lag screws 30, is a sleeved supporting member 31 having vertically extending stop projections 32 and 33 and a spiral track 33^a extending between said projections. Rigid with the shaft 26 is a coöperating member 34 having a hub portion 35 carrying a spiral rib 36 one end 37 whereof, coöperates with 20 the stop projection 32, and the other whereof coöperates with the stop projection 33. The lower surface of the rib 36 is inclined complementarily to the inclination of the track 33, there being rollers 38 mounted in recesses 25 provided in the lower surface of the rib 37, said rollers moving along the track 33. 39 denotes a cup which is adjustable along the shaft 26 by means of a nut 40 threaded on the lower end of said shaft, there being a 30 lock-nut 41 below the nut 40 for the purpose of retaining the latter, and the cup 39 in any position to which they may be adjusted. Surrounding the lower portion of the shaft 26 is a helical spring 42, the lower 35 end whereof extends within the cup 39 and is connected to the shaft, the upper end of said spring engaging a lug 43 projecting downwardly from the plate 25.

On the upper surface of the rib 37 is a 40 locking projection 37^a extending transversely of said rib and being angular in outline. The lower end of said rib constitutes a stop projection which coöperates with the projection 32.

Secured to the plate 25 at one side of the 45 members 31 and 34 is a block 44. The face of this block which is presented toward the members 31 and 34 is concave. Extending through said block are rods 45, said rods 50 being threaded and provided with nuts 46 to secure them in position and clamp the block to the plate 25, the upper ends of the rods projecting through the head-plate 47 having a central aperture for the upper end 55 of a rod 48 having a collar 49 thereon above said block, there being a helical spring 50 interposed between said collar and the plate 47. The portion of the rod 48 which extends through the block 44 is preferably angular 60 in section and slides within a similarly shaped bore through said block, whereby the rod may reciprocate with respect to said block without rotating. Projecting from the rod 48 above the block is a locking dog 65 51 adapted to overhang the rib 36 and hav-

ing an angular notch 52 therein adapted to receive the angular locking projection 37^a on said rib and thereby prevent the rotation of the shaft 26 by the spring 42.

The rod 48 is preferably made in two 70 parts having reversely threaded ends connected by a correspondingly threaded sleeve 53, enabling the effective length of said rod to be varied. The lower end of the rod projects through an opening in the web 24 and 75 is connected to one end of a lever 54, which may be conveniently pivoted to the flanges 23^a, the opposite end of said lever being provided with a vertical extension or blade 55 projecting through the web 24 and a 80 guide block 56 secured thereto, the upper surface of said block being beveled downwardly in opposite direction from said blade.

With the parts constructed and arranged 85 as described, the operation will be as follows:—

The mail crane shaft having been set and locked with its arms 27 and 28 projecting parallel with the track, as by means of the 90 handwheel 57, and a mail bag having been applied to said arms in the usual manner, the plate 55 will project through the guide-block 56 from about $\frac{1}{2}$ to $\frac{3}{4}$ inch. The operator on the mail car sets the catcher in the 95 position shown in Fig. 1, thereby depressing the roller 18 to about the level of the top of the rail 1. This roller will be carried some 35 or 40 feet in advance of the catcher in order to depress the blade 55 and permit 100 the spring 42 to throw the shaft 26 and thus bring the arms and the mail bag carried thereby in operative relation to the catcher before the latter reaches the bag. Should the roller project somewhat below the blade 105 55, as is preferable, it will ride up the inclined surface of the block 56, before depressing the said blade, thereby rocking the lever carrying said blade and lifting the dog 51 above the locking projection 37^a. 110 The resiliency of the spring 42 permits such slight rocking of the main crane shaft as will allow the angular lower face of the dog to clear the angular side face of said projection. Immediately upon the release 115 of the dog from the locking projection, the spring 42 will rotate the shaft 26 to the position shown in Fig. 1, the shaft moving downwardly during such rotation, and the catcher will remove the mail bag in the usual manner, the arms 27 and 28 thereupon swinging to vertical position, as is customary. The operator for the crane can then apply another mail bag to these arms and reset the shaft through the handwheel 57. During 120 this operation, the shaft 26 will be elevated by reason of the rollers 38 running upon the track 33 until such time as the locking projection 37^a catches beneath the dog 52. Unnecessary rotation of the shaft 26 is pre- 130

vented by reason of the stops 32 and 33 which are arranged to limit such rotation to approximately one-quarter revolution.

Having thus described my invention what I claim is:

1. The combination, with a track and a car movable therealong, of a rotatable mail crane shaft, means tending to rotate said shaft, a locking member carried by said shaft, a rod extending parallel with said shaft and having a locking member coöperating with the first mentioned locking member, yielding means tending to hold said locking members in engagement, and means operable from said car for moving said rod thereby to disengage its locking member from the first mentioned locking member.

2. The combination, with a rotatable mail crane shaft, of a projection carried thereby, a locking device carried by such projection, a supporting device having an inclined track located beneath said projection, anti-friction means interposed between said projection and said track, means tending to rotate said shaft, stops coöperating with said shaft to limit the rotary movement thereof in opposite directions, a rod extending parallel with said shaft and having a locking member coöperating with the first mentioned locking member, means engaging said rod for yieldingly holding said locking members in engagement, and means for operating said rod against the resistance of such yielding means for disengaging said locking members.

3. The combination, with a rotatable mail crane shaft, of a rib projecting therefrom, one or more rollers on the under side of said rib, an angular locking device on said rib, a supporting device having an inclined track for said roller or rollers, a spring surrounding said shaft and connected thereto and tending to rotate the shaft as well as to move the same in the direction of its length, stops coöperating with said rib to limit the rotary movement of said shaft, a rod extending parallel with said shaft and having a locking member coöperating with the first mentioned locking member, a spring coöperating with said rod to hold said members in such locking engagement, and means for operating said rod against the action of the spring thereby to disengage said locking members.

4. The combination, with a track and a car movable therealong, of a longitudinally adjustable and rotatable shaft, a mail bag support thereon, means tending to rotate said shaft in a direction to bring the mail bag support in operative relation to said track and car, a projection carried by said shaft, an inclined support for said projection and along which said projection is adapted to move, means coöperating with said projection and support for limiting the rotary movement of said shaft in opposite direc-

tions, a locking member carried by said shaft, a coöperating locking member, means tending to hold said locking members in operative relation to each other, and means operable from the car for disengaging the second locking member from the first mentioned locking member.

5. The combination, with a track and a car movable therealong, of a rotary mail crane shaft, a spring surrounding said shaft and connected thereto and tending to rotate said shaft as well as to move the same longitudinally, a projection carried by said shaft, a support partly surrounding said standard and having an inclined track, anti-friction means interposed between said projection and said track, stops carried by said supporting member and adapted to limit the rotation of said shaft in opposite directions, a locking member carried by said shaft, a reciprocable rod adjacent to said shaft, a locking member carried thereby and coöperating with the first mentioned locking member, a spring surrounding said rod and normally holding said members in engagement, and means, operable from the car, for moving the rod in a direction to release its locking member from the first mentioned locking member.

6. The combination, with a track and a car movable therealong, of a rotatable and longitudinally adjustable mail crane shaft, means connected to said shaft and tending to rotate the same as well as move it longitudinally, a spiral rib projecting from said shaft, a support partly surrounding said shaft and having a spiral path on the upper portion thereof and provided with stop projections at the upper and lower ends of said path, anti-friction devices interposed between said rib and said path, an angular locking projection on the upper surface of said rib, a reciprocable rod extending parallel with said standard, a locking dog carried by said rod and having an angular recess coöperating with the angular locking projection, an adjustable spring tending to hold said rod with its dog in operative relation to the said locking projection and means operable from said car for moving the rod in a direction to disengage said dog from said locking projection.

7. The combination, with a rotatable mail crane shaft, of a rib projecting therefrom and having spiral upper and lower surfaces extending partly about said shaft, an angular locking device on the upper surface of said rib, a supporting device having an inclined track, anti-friction devices interposed between said track and the lower surface of said rib, a spring surrounding said shaft and connected thereto and tending to rotate the shaft as well as to move the same downwardly, stops coöperating with said shaft to limit the rotary movement thereof in op-

posite directions, a reciprocable device having an angularly notched locking member adapted to overhang the upper surface of said rib and engage the locking member thereof, means cooperating with said device for yieldingly holding its locking member in engagement with the first mentioned locking

member, and means for operating said device against the action of such yielding means, thereby to disengage said locking members. 10

In testimony whereof I hereunto affix my signature.

GARRETT J. BARRY.
